BILLFOLD

Alfred Petersohn and William H. St. Thomas,
West Bend, Wis., assignors to Amity Leather
Products Co., West Bend, Wis., a corporation
of Wisconsin

Application December 3, 1934, Serial No. 755,716

9 Claims. (Cl. 150—38)

This invention relates to billfolds and more particularly to billfolds of the single fold type.

The general purpose and object of our invention is to provide a construction wherein the billfold will have a large number of card and other memoranda receiving pockets at its opposite ends and several compartments extending longitudinally of the billfold for the reception of paper currency, checks, notes, and the like, in spread 10 out or unfolded form.

A further object of our invention is to provide a construction wherein the inner wall section and the upper longitudinal portion of the associated partition wall section of the billfold may respectively move and yield longitudinally relatively to the outer wall section to avoid buckling in folding the billfold on its fold line between the ends of and transverse to said wall sections, the result being that the overlapping portions of the 15 billfold when folded will lie relatively flat as required for an effective billfold device.

A further object of our invention is to so connect the partition wall section of the billfold with the parts to which the partition wall section 25 is attached that the partition wall section may respond to the folding action of the billfold to avoid buckling.

A further object of our invention is to accomplish this result with respect to the inner wall 30 section by having one end of said section directly attached to the outer wall section and the other end connected within the outer wall section by a yieldable element of fabric or other desired flexible material.

A further object of our invention is to accomplish the result stated with respect to the partition wall section by having said section connected by an interlocking tongue and slot construction with the pocket forming wall members which 35 support the partition wall section whereby the latter may slide with respect to said wall members and the outer wall section to avoid buckling in folding the billfold.

The invention consists further in the matters 40 hereinabove described and claimed.

In the accompanying drawings:

Fig. 1 is a plan view of the wall members employed with the inner wall section of the billfold to form pockets at the opposite ends of said section, said wall members being shown removed from the inner wall section;

Fig. 2 shows the wall members of Fig. 1 assembled with the inner wall section of the billfold preparatory to folding into overlapping relation 45 therewith;

Fig. 3 shows the assembly of Fig. 2 folded into overlapping relation;

Fig. 4 is a plan view of the outer wall section of the billfold;

Fig. 5 is a similar view showing the partition 5 wall section of the billfold laid in proper position on the outer wall section and with pocket forming wall members connected with the partition wall section by the interlocking slot and tongue arrangement heretofore referred to;

Fig. 6 shows the inner wall assembly of Fig. 3 laid on the partition wall section of Fig. 5;

Fig. 7 shows the wall forming members attached to the partition section folded over the 10 inner wall assembly;

Fig. 8 shows the completed billfold;

Fig. 9 is a plan view showing the interlocking slot and tongue construction referred to, the parts being separated for the purpose of illustration; and

Fig. 10 is an enlarged transverse sectional view taken on line 10—10 of Fig. 8.

The various sections of the billfold, excepting the fabric section to be hereinafter referred to, are blanked out to the size and shape required from the desired flexible material employed for the billfold construction. Leather is usually the material employed for billfolds and the various sections referred to are blanked out of such material. The color and the surface ornamentation 20 for the billfold will depend upon the material selected for the device.

The inner wall section of the billfold, as shown in Fig. 2, has a body portion 1 of a length more than half the length of the billfold and a flexible fabric portion 2 secured, as by stitching to one end of the body portion 1. The body portion 1 extends across the transverse fold line of the billfold and has an integral outwardly extending co-planar projection 3 at its end opposite the fabric portion 2. The projection 3 is disposed between the upper and lower edges of the body portion 1 and provides means for connecting the adjacent end of the body portion 1 to the outer wall section of the billfold as will presently appear. The fabric portion 2 is secured to the opposite end of the outer wall section and allows longitudinal movement of the body portion 1 to avoid buckling in folding and unfolding the billfold. The fabric portion 2 is slightly shorter 50 than the width of the body portion 1 so that certain of the pocket forming wall members to be presently described may be secured together below the lower edge of the fabric portion as indicated in Fig. 2.

The pocket forming wall members just referred to comprise three separately formed members 4, 5, and 6 as shown in Fig. 2. The member 4 is secured, as by stitching 7, to the upper edge of the body portion 1 of the inner wall section on one side of its fold line. The member 4 is secured to the inner side of the portion 1 along its upper edge and is folded over that edge to overlap the outer side of the portion 1 and form therewith a card or the like receiving pocket at one end of the billfold as shown in Fig. 3. The member 4 extends to the lower edge of the portion 1 and is provided at its lower outer corner with an integral extension 8 by which the member 4 may be secured to the outer wall section to hold the member 4 in its pocket forming position over the body portion 1. The extension 8 lies below the extension 3 to be engaged by the same line of stitching and to avoid bulkiness at the end of the billfold.

The members 5 and 6 are secured together as by stitching 9 along their adjacent overlapping longitudinal edges to provide a section having a width twice that of the body portion 1. The members 5 and 6 are folded into overlapping relation along their line of juncture and provide an enclosing structure for the end of the body portion 1 at its fabric portion 2 as indicated in Figs. 2 and 3. The members 5 and 6 are folded over the upper edge of the body portion 1 and not only provide a guide for the inner wall section in its endwise movement, but provide end pockets for the billfold on the side of the fold line opposite the pocket formed by the member 4. With the fabric portion 2 terminating short of the lower edge of the body portion 1, the members 5 and 6 may be secured together as by pasting along their marginal edges beyond the lower edge of the fabric section as indicated at a in Fig. 3. The members 5 and 6 have end extensions 10, 11 whereby said members may be secured to the outer wall section of the billfold for holding said members in overlapping relation with the inner wall section. The extensions 10 and 11 are so disposed on their respective wall members, that the extensions do not overlap when the wall members are in folded relation as shown in Figs. 2 and 3. This avoids bulkiness at the end of the billfold. These extensions overlap the fabric portion 2 and thus may be engaged by the line of stitching which secures the fabric portion to the outer wall section of the billfold. As shown in Fig. 3, the pockets formed by the wall members 4, 5 and 6 open toward each other and are disposed on opposite sides of the fold line of the billfold, which fold line is approximately along the section line 10—10 in Fig. 8, and is marked b in the other figures where indicated. With the wall members 4 to 6 carried by the body portion 1, the assembly provides a unit for the inner wall section of the billfold.

The blank for the outer wall section of the billfold is shown in Fig. 4. The blank has a body section 12 of the length and width required for the billfold and is provided with a pair of flaps 13, 14 along its lower longitudinal edge. These flaps are on opposite sides of the fold line of the billfold and are separated by a tab 15 integral with the wall section 12 and folded over and pasted thereto on its inner side to reinforce the lower edge of the section 12 where the wall is folded on the fold line b. The upper longitudinal edge of the section 12 is reinforced by a marginal flap 16 integral with the section and folded over and pasted thereto as shown in Fig. 4. Section 12

also has integral end flaps 17, 18 which flaps are folded over the section 12 and are employed to close the ends of the billfold in the completed device. The flaps 13 and 14 are angled off along their inner edges so that other flaps which form pockets, to be hereinafter referred to, are exposed to indicate the presence of the pockets and to permit ready accessibility thereto.

The bill fold is provided with a partition wall section 19 as shown in Figs. 5 to 8. This section 19 is laid on the inner side of the wall section 12 when assembling the billfold and extends crosswise and lengthwise of the section 12, as shown in Fig. 5. The section 19 is provided with a pair of pocket forming wall members 20, 21. These members are connected to the upper edge of the partition 19 at its opposite ends and are foldable over the partition into overlapping relation with the inner wall section and its pocket forming members 4 to 6 after such unit has been placed on the partition 19 as shown in Figs. 6 and 7. The members 20, 21 are formed independently of the partition 19 and are connected therewith by a tongue and slot construction as shown in Figs. 5, 6, and 9. This construction comprises an elongated slot 22 in the partition for each of the members 20 and 21. These slots are arranged substantially parallel to the upper and lower edges of the partition and are located adjacent the opposite ends of the partition near its upper edge. The members 20, 21 are each provided with a tongue 23, which tongues are insertable into the slots 22 for interconnecting the members 20, 21 with the partition 19 as clearly shown in Fig. 5. The tongues 23 are also elongated so that they will retain their connection with the partition as its upper longitudinal portion moves or yields longitudinally in the folding and unfolding of the billfold, which movement is permitted by the elongated slots and the fact that the partition remains otherwise disconnected in the billfold construction except for the herein-after mentioned tabs which do not hinder such movement of the partition to avoid buckling in folding and unfolding the billfold. The tongues 23 are made elongated by cutting slots 24 in the members 20, 21 at the tongues, as shown in Fig. 9. These slots are substantially parallel to the slots 22 when the parts are in assembled relation as shown. The slots 24 open through the end edges of the members 20, 21 so that the tongues 23 may be inserted into the slots 22.

The members 20, 21 are folded over the upper edge of the partition 19 on fold lines 25, 25 to be on the oversides of the inner wall section 1 and its pocket forming wall members 4 and 5, as shown in Fig. 7. The members 20, 21 are so folded after the inner wall section has been placed on the partition 19, as shown in said figure. The members 20, 21 extend close to the lower edge of the inner wall section and provide pockets with the wall members 4, 5 of that section. The inner or opposed edges of the members 20, 21 are angularly cut away, as shown in the drawings, so that said members will expose portions of the wall members 4, 5 to make their pockets readily discernible and also to allow access to be had to the pockets formed by the members 20, 21 along their free upper edges. In addition to being secured to the outer wall section 12 beyond the ends of the partition 19, which is made short enough for the purpose, the members 20, 21 are retained in their pocket forming relation by tabs 26, 26 on the partition 19 at its lower edge. These tabs are on opposite

sides of the fold line of the billfold and are folded over the lower edges of the inner wall section 1 and its pocket forming wall members 4, 5, and 6 and also over the lower edges of the members 20, 21 when the parts are assembled as shown in Fig. 7. The tabs 26 are located adjacent the opposed ends of the members 20, 21 and are secured, as by pasting, to the outer sides of said members. To avoid bulkiness at the tabs, the members 4, 5 are notched at 27, 27 where the extensions 28, 28 on the members 20, 21 extend to be engaged by the tabs.

After the parts have been assembled as in Fig. 7, the flaps 13, 14 on the outer wall section 12 are folded upwardly along the lower edge of said section to overlap the wall forming members 20, 21 and also the tabs 26 which are concealed by the flaps 13, 14 as is apparent from Fig. 8. The flaps 17, 18 at the ends of the outer wall section 12 are then folded over the flaps 13, 14 and are secured thereto by pasting and by lines of stitching 29, 29, one at each end of the billfold. The flaps 17, 18 close the ends of the several pockets at the ends of the billfold and also close the ends of the longitudinal compartments which are provided between the partition 19 and the inner and the outer wall sections 1 and 12, respectively. The flaps 13, 14 close the lower edges of these pockets and also the lower edges of the compartments, except for the short distance between the flaps in the region of the fold line b. As before stated, the flaps 13, 14 are angled off to expose the wall forming members 20, 21 and also to permit access to be had to the pockets which they provide at the opposite ends of the billfold.

The stitching 29 also engages the outer wall section 12, the wall forming members 20, 21, the fabric section 2, the extension 3 on the inner wall section 1, and the extensions 8, 10, and 11 on the wall forming members 4, 5, and 6, respectively. Thus, the parts referred to are secured together and in place in the billfold construction. The ends of the partition 19 terminate short of this stitching and thus the upper longitudinal portion of the partition is free to slide or move endwise to avoid buckling in folding the billfold. Also the fabric section 2 permits the inner wall section 1 to yield or slide in this movement, and buckling of this section is avoided. This is an important feature of the construction as the billfold is retained flat when its parts are folded and overlapped even though carrying cards, checks, and paper currency in its respective pockets and compartments.

As shown in Fig. 8, cutting away of the various wall forming members for the pockets along inclines indicates the presence of the pockets and also exposes portions of the wall forming members whereby access may be readily had to the pockets. It will be noted from Fig. 8 that the billfold is provided with three end pockets at each end of the billfold and that the pockets are on opposite sides of the fold line b. The innermost end pockets, marked A, A, are accessible from the outer side of the inner wall forming section 1 and these pockets open inwardly toward the fold line b. The next two pockets, marked B, B, also open inwardly toward the fold line and also open upwardly along the inclined upper edges of the wall members 20, 21, respectively. The next two pockets, marked C, C, are similarly arranged and accessible. The pocket formed by the wall member 6 is behind the section 1 and its fabric portion 2, as shown in Fig. 2.

The longitudinally extending compartments heretofore referred to are marked D and E, respectively, in Figs. 8 and 10. The compartment D is formed by the partition 19 and the outer wall 12. The compartment E is formed by the partition and the inner wall section 1. These compartments are provided to receive checks, notes, and paper currency, respectively. The compartment D opens along the full length of the billfold. The compartment E also opens along the full length of the billfold, except where it is embraced at its ends by the portions of the wall members 20, 21 where they fold over the upper edge of the partition. These portions are relatively short and do not hinder accessibility to the compartment E.

One of the important features of the billfold construction herein disclosed is with respect to enabling relative longitudinal movement to be had with respect to the inner wall section 1 and the partition wall section 19. The flexible fabric section 2 provides for this movement with respect to section 1, while the interlocking tongue and slot construction heretofore described provides for this movement with respect to the partition wall section 19. This has the advantage of avoiding buckling of the billfold along the line of fold and thus the folded sections may be retained in flatwise relation even though the billfold is carrying checks, notes, memoranda cards, etc. in its various pockets and longitudinal compartments.

Another important feature of the invention is with respect to having the wall forming members 5 and 6 embrace the inner wall section 1—2 over one longitudinal edge. This not only provides end pockets at these members, but also provides a compartment in which the wall section 1 and its fabric section 2 are slidably mounted. This construction also avoids the necessity and expense of a duplicate fabric section, one at each end of the inner wall section 1 as in billfold constructions heretofore placed on the market. In addition, the construction is extremely simple and is of a character not only enabling the billfold to be readily assembled, but avoids the expense of excessive stitching, thereby producing a construction which can be manufactured commercially on a large production basis. Also the billfold has a large number of end pockets at opposite ends of the construction, which pockets are not only readily accessible and visible, but have a slanting or inclined appearance on the inside of the billfold which adds greatly to its ornate features.

The details of construction and arrangement of parts shown and described can be variously changed and modified without departing from the spirit and scope of our invention, except as pointed out in the appended claims.

We claim as our invention:

1. In a billfold of the character described, overlapping wall sections providing a compartment extending longitudinally of the billfold and opening along the upper longitudinal edge thereof, pocket forming wall members at the opposite ends of said wall sections and secured at their outer ends to the outer ends of the outermost wall section, and means connecting the innermost wall section to the pocket forming wall members comprising tongues at the upper edges of said wall members adjacent their outer ends and having interlocking connection with elongated slots in the adjacent portions of the innermost

wall section, and tabs at the lower edge of the innermost wall section overlapping and secured to the adjacent portions of said wall members at their inner lower ends.

5. 2. In a billfold of the character described, inner and outer wall sections extending longitudinally of the billfold, said inner wall section being secured at one end only to the outer wall section at one end of the billfold and having its opposite end terminating short of the other end of said outer wall section, a flexible section connecting the last named end of the inner wall section to the adjacent end of the outer wall section, whereby the inner wall section may have longitudinal movement relatively to the outer wall section in folding the billfold, and pocket forming wall members at the opposite ends of the inner wall section and secured at their outer ends to the outer ends of the outer wall section, 10 the wall member at one end of the billfold being also secured to the inner wall section along one longitudinal edge thereof and overlapping the outer side of said section, the wall member at the opposite end of the billfold embracing the 15 inner wall section over the flexible section and having portions on opposite sides of the flexible section and the adjacent portion of the inner wall section and secured together along one edge of the flexible section.
30. 3. In a billfold of the character described, inner and outer wall sections and an interposed partition wall section, said sections being arranged in overlapping relation and providing compartments extending longitudinally of the 35 billfold and opening along the upper edge thereof, pocket forming wall members at each end of the billfold and disposed on opposite sides of the transverse fold line thereof, certain of said wall members being associated with the inner wall 40 section and forming therewith pockets terminating short of the fold line and opening toward the same, the others of said wall members overlapping the first mentioned wall members and forming therewith pockets opening upwardly along 45 the upper edges of the second mentioned wall members, means connecting the second mentioned wall members with the partition wall section over the upper and the lower edges of the inner wall section, and flaps carried by the outer 50 wall section and overlapping the pocket forming wall members to close the compartments and the pockets at their ends and along their lower edges, respectively, certain of said flaps overlapping the second mentioned wall members and forming 55 therewith pockets which open along the upper edges of said flaps.
4. In a billfold of the character described, inner and outer wall sections and an interposed partition wall section, said sections being arranged in 60 overlapping relation and providing compartments extending longitudinally of the billfold and opening along the upper edge thereof, wall members secured to the outer wall section at the opposite ends of the billfold and overlapping the inner wall section on the outer side thereof to provide pockets at the opposite ends of the billfold, said wall members having portions having 65 an interlocking connection with the partition wall section, and extending over the upper edges of the inner and partition wall sections, respectively, at the ends of the billfold, and tabs connecting the partition wall section to said wall members at the lower edge of the partition wall section to maintain the wall members in overlapping relation with the inner wall section.

5. In a billfold of the character described, overlapping wall sections providing a compartment extending longitudinally of the billfold and opening along the upper longitudinal edge thereof, pocket forming wall members at the opposite ends 5 of said wall sections and secured at their outer ends to the outer ends of the outermost wall section, and means connecting the innermost wall section at its upper and lower longitudinal edges to the pocket forming wall members, the connection between the lower edge of the innermost wall section and the pocket forming wall members being adjacent the outer ends of the latter and comprising an interlocking formation constructed and arranged whereby the upper longitudinal portion of said innermost wall section may yield longitudinally of the billfold with respect to the wall members in folding and unfolding the billfold on a fold line intermediate the ends of and transverse to said wall sections.

6. In a billfold of the character described, overlapping wall sections providing a compartment 25 extending longitudinally of the billfold and opening along the upper longitudinal edge thereof, pocket forming wall members at the opposite ends of the billfold and secured at their outer ends to the outer ends of the outermost wall section, and means connecting the innermost wall section at its upper and lower edges to the pocket forming wall members, the connections between the upper edge of the innermost wall section and the pocket forming wall members being adjacent 30 the ends of the innermost wall section and comprising an interlocking formation constructed and arranged whereby the upper longitudinal portion of said innermost wall section may yield longitudinally of the billfold with respect to the 35 wall members in folding and unfolding the billfold on a fold line intermediate the ends of and transverse to said wall sections.

7. In a billfold of the character described, overlapping wall sections providing a compartment 45 extending longitudinally of the billfold and opening along the upper longitudinal edge thereof, pocket forming wall members at the opposite ends of the billfold and secured at their outer ends to the outermost wall section, and means connecting the innermost wall section at its upper and lower edges to the pocket forming wall members, the connection between the upper edge of the innermost wall section and each pocket forming 50 wall member comprising an extension on the wall member embracing the upper edge of the innermost wall section and having a tongue interengaged with a longitudinally extending slot in the innermost wall section.

8. In a billfold of the character described, overlapping wall sections providing a compartment 60 extending longitudinally of the billfold and opening along the upper longitudinal edge thereof, a pocket forming wall member at one end of the billfold and secured at its outer end to the outermost wall section, and means connecting the innermost wall section at its upper and lower edges to said pocket forming wall member, the connection between the upper edge of the innermost wall section and the pocket forming wall member comprising a longitudinally extending slot in the innermost wall section and an extension 65 on the wall member embracing the upper edge of the innermost wall section and having a tongue interengaged with said slot.

9. In a billfold of the character described, overlapping wall sections providing a compartment extending longitudinally of the billfold and opening along the upper longitudinal edge thereof, a pocket forming wall member at one end of the billfold and secured at its outer end to the outermost wall section, and means connecting the innermost wall section adjacent its upper edge to

the pocket forming wall member, said means comprising a longitudinally extending slot in the innermost wall section and an extension on the wall member embracing the upper edge of the wall section and having a tongue interengaged with said slot. 5

ALFRED PETERSOHN.
W. H. ST. THOMAS.
